UNITED STATES PATENT OFFICE.

PEHR NILSSON, OF NEW YORK, N. Y.

CAR-FENDER.

SPECIFICATION forming part of Letters Patent No. 634,092, dated October 3, 1899.

Application filed April 7, 1898. Serial No. 676,734. (No model.)

To all whom it may concern:

Be it known that I, PEHR NILSSON, a citizen of the United States of America, and a resident of New York, (Brooklyn,) county of 5 Kings, and State of New York, have invented certain new and useful Improvements in Car-Fenders; of which the following is a specification.

My invention has relation to car-fenders, 10 and especially to that class which is employed in street or surface cars and usually called "life-saving" fenders; but my improvements may be adopted on fenders for vehicles of any kind whereon they could be utilized to 15 advantage.

The objects of my invention are to provide a simple, cheap, effective, and easily-operating means for controlling the movements of the fender from the car-platform, holding the 20 fender securely until occasion requires it to be dropped, and then permitting its instant release, and to supply means for holding the fender against the action of its springs when necessary to detach the fender from the car. 25 To accomplish these objects and to secure other advantages in construction, operation, and use, my improvements involve certain new and useful arrangements or combinations of parts and peculiarities of construction, as 30 will be herein first fully described and then pointed out in the claims.

In the accompanying drawings, forming part of this specification, Figure 1 is a vertical side view, partly in section, showing my 35 improved fender mounted upon a street-car and in the position in which it ordinarily travels—that is, with the lower end free from the road-bed. Fig. 2 is a corresponding plan view of the same, portions being broken out 40 or away to better expose some features of the construction. Fig. 3 is a sectional elevation of a fragment, showing the pedal and its lock by which the fender is held and released.

In all the figures like letters of reference, 45 wherever they occur, indicate corresponding parts.

A A are side bars of proper size and shape for supporting the fender, the same being connected by the fender-axle and by any suitable 50 cross-bar, as B. The side bars enter suitable sockets, as C C, with which the car is supplied, being easily removable therefrom when

required to shift the fender from one end of the car to the other or for other purposes, and the side bars are maintained against accidental displacement by suitable cross-pins, as a.

The fender-frame swings slightly on the side bars A A, being connected therewith by a cross-rod D, which operates as an axle for the 55 frame, thus enabling the lower end of the fender to be swung from the road-bed or to be lowered upon it. Ordinarily the fender travels in about the position and relation indicated in Fig. 1. It is held in this position 60 (against the action of the springs to be hereinafter referred to) through the medium of suitable bars, as E E, applied to its upper end and through the pedal-shaft F. The bars E E are located one on one side and the 65 other on the other side of bar B and they join at the bottom, substantially as shown, so as to form a bearing for the pedal-shaft. When the pedal-shaft is pushed down, as it may be by the foot of the driver or motorman, it effects the lowering of the upper end of the 70 fender (thus raising the lower end) and compresses the springs G G. It should be locked in its lowered position, so as only to be released when required, and for this purpose I 75 supply the shaft with notches, as shown in Fig. 3, and arrange the same to be caught by a latch or detent b. This latch is pivoted, as at c, and has a tongue d, arranged to project slightly above the level of the platform. A 80 light spring, as f, holds the latch in engagement with the notch in the shaft until purposely disengaged. The latch and its spring are located in a box, preferably of metal, which may be let into the floor of the platform, so that its upper part will not form an 85 obstruction on the floor, and the cover of this box is made removable, as indicated, and is provided with a curved slot, through which the tongue d may project. The tongue is to 90 be moved by the foot of the driver or motorman, and the instant it is moved the pedal-shaft will be released and the springs G will 95 depress the lower end of the fender in the manner required, all of which will be easily 100 understood.

While shifting the fender the spring G should be held in compressed position; otherwise it would be difficult to readjust or relo-

cate the fender. I therefore supply the cross-bar B with any suitable form of hook, as H, the same being arranged to ride upon the cross-bar when the car and fender are in use, but ready to be turned up and engaged with the upper bar I of the fender before the fender is detached from the car. To release the fender, the pedal is depressed slightly, the hook H turned up to engaging position, the bolt or pin a withdrawn, and the pedal-shaft 10 lifted out of engagement with the ends of bars E E.

In the lower part of the fender is a shaft K, which with its covering constitutes a roller for contact with the pavement or road-bed when the fender is forced to swing down far enough. This shaft is covered with rubber or equivalent yielding substance of considerable thickness, as indicated at L, and consequently contact of the roller with the road-bed will always be yielding, so that the fender will not be damaged, and the roller enables the fender to pass over unyielding objects with greater facility and with much less shock than would result from the use of a rigid bar at this part of the device. Along the lower front edge of the fender and projecting over roller L is a shield M. This is made of sheet metal, so as to afford a means of closer contact with the road-bed than is possible with any form of roller, the intention and effect of the construction being that the shield shall ride beneath any object however small and force the same to a position on the fender. Thus, for instance, a child's hand would be raised by the shield, whereas it would only be damaged by any form of device which could pass over it. The shield M is covered and protected by rubber, as at M', so as to make its contact with any object as little damaging as possible.

Both the side rails N N of the fender are covered with rubber or elastic tubing, as N' N', to obviate injury to bodies caught upon

the fender. This covering is easily applied and will be found to admirably answer the purposes intended. The netting is made easily removable from the fender, so that it may be easily repaired or replaced.

I supply the fender with rods or bars, as O O, on each side and hold them in place by detachable screws, as e e. On removing the screws e e the rods O O and all the netting may be at once dismounted. The rods O may then be easily withdrawn from the netting and the latter replaced by a new one, if desired. This does not require that the fender be left at the shops for repairs, as is ordinarily necessary, but may be easily accomplished by the carmen at any time desired.

The fender constructed and arranged substantially in accordance with the foregoing explanations will be found to answer all the purposes or objects of the invention previously set forth.

Having now fully described my invention, what I claim as new herein, and desire to secure by Letters Patent, is—

1. In combination with the pedal-shaft notched as explained and passing through the car-platform, the hinged latch, latch-spring and projecting tongue, the latch and latch-spring being located in a covered box, substantially as shown and described.
2. In a car-fender, the combination with the axled fender-frame, cross-bar B and springs G G, of a hook applied on the cross-bar and arranged to hold the fender against the action of the springs, to facilitate shifting of the fender, substantially as shown and described.

Signed by me at New York, N. Y., this 31st day of March, 1898.

PEHR NILSSON.
